UNITED STATES PATENT OFFICE.

WILLIAM L. RODGERS, OF PITTSBURGH, PENNSYLVANIA.

WASHING MACHINE.

Application filed October 3, 1922. Serial No. 592,109.

To all whom it may concern:

Be it known that I, WILLIAM L. RODGERS, a citizen of the United States, and a resident of Pittsburgh, in the county of Allegheny 5 and State of Pennsylvania, have invented a new and useful Improvement in Washing Machines, of which the following is a specification.

This invention relates to washing machines, and particularly to the means for removably mounting an oscillating tub upon its supporting frame and the detailed construction of the said tub.

It is an object of the invention to so associate the several parts of the supporting frame, the gearing for causing oscillation of the tub, the bearings for the trunnions of the tub, and the connection between the gearing and the tub in such fashion that 20 the tub may be easily and readily removed and as readily replaced within the frame.

It is a special object of the invention to provide a driving connection between the gearing and the oscillating tub at one end 25 thereof comprising a crank arm provided with a radial slot for receiving a trunnion block attached to the tub, and disposing the parts so that the said crank arm will normally depend under the influence of gravity 30 for the purpose of vertically positioning the slot therein, to enable the tub being as readily replaced in operative position within the frame as it can be removed therefrom by vertically lifting same.

It is also a special object of the invention 35 to provide an oscillating tub for washing machines which is simple in construction, easy to manufacture, sanitary, which is extremely durable, and which is effective and 40 noiseless in operation.

It is still a further special object of the invention to provide an oscillating tub provided with a perforated false bottom, spaced from the bottom of the main body thereof, 45 which is corrugated throughout substantially its entire extent, and having the perforations so disposed as to avoid any deleterious action upon the clothes during the washing operation.

Further special objects of the invention 50 are to provide a tub readily permitting the passage of dirt to a sediment-collecting chamber and drain trough disposed below the false bottom and equipped with means 55 for effectively disposing of such sediment and dirt, to so connect the false bottom with

the body and end walls of the tub as to leave no open spaces into which the clothes may catch during washing and be gripped therein due to flexion of the parts; to provide a 60 false bottom of inverted V-shape having the portion which connects the sloping sides thereof removable so as to facilitate ready access to the sediment-collecting chamber, to provide a tub in which a rubbing action upon 65 the clothes is constantly effected during its entire operation; and to provide a tub having trunnion supporting spiders which are so connected therewith as to prevent any 70 relative movement therebetween thus avoiding their becoming loose and noisy due to wear of the parts even after long use.

These and other objects of the invention will more readily appear when taken in connection with the following description and 75 the appended claims.

In the accompanying drawings, Fig. 1 is a plan view, with a portion of the side frame members broken away, illustrating the means employed for mounting the oscillating tub 80 within the supporting frame; Fig. 2 a vertical sectional view, with parts in elevation, taken on the line II—II of Fig. 1; Fig. 3 a view partly in section and partly in elevation showing the construction of one 85 of the spiders of the tub; Fig. 4 a view, similar to Fig. 3, showing the construction of the spider mounted at the opposite end of the tub; and Fig. 5 an enlarged detailed 90 sectional view taken on the line V—V of Fig. 1 illustrating the construction and method of mounting of the false bottom spaced from the bottom of the tub to form a sediment-collecting and drain chamber.

The frame of the machine comprises the side frame members 1, 2, and the end frame members 3, 4, connected together in any suitable manner, as by riveting, so as to procure a rigid construction, the entire frame being supported upon casters indicated at 5, 5'. Fixed to the end frame member 3 is a plate 6 having integrally formed therewith the open-topped trunnion bearing 7 for receiving the cylindrical trunnion 8 projecting from the spider 9 attached to one end wall 105 of the tub in a manner to be presently described.

Fixed in any suitable manner to the end frame member 4 is a gear housing 9 containing the gearing for causing oscillation of the tub. The details of this gearing form no 110 part of the present invention, except in so

far as it is finally connected to the oscillating tub, and for that reason it has not been illustrated nor described in greater detail. Said gearing, however, terminates in a rock shaft 10 having a depending crank arm 11 attached thereto. The crank arm 11 extends downwardly below the axis of the shaft 10, normally hanging in a vertical position, due to the action of gravity upon the parts, and 5 is provided with an open-topped vertical slot 12 at the lower extremity of which is disposed an abutment lug 13. A substantially rectangular trunnion-block 14, formed integrally with the spider 15 attached to the 10 end wall of the tub, is adapted to fit within the slot 12, with the lower end of the block resting upon and supported by the abutment lug 13. Because both the bearing 7 and the slot 12 are open-topped, the tub may be 15 readily removed by merely lifting the same vertically, and due to the action of gravity which maintains the crank arm 11 normally in a vertical position when the source of driving power is disconnected therefrom, the 20 tub may be readily replaced in operative position within the frame. This feature of applicant's construction is of great practical importance, since it not only enables the tub to be easily and quickly removed and replaced whenever desired, but facilitates the 25 handling of the washing machine in transporting from place to place. The tub is of such proportions and weight that it can be easily handled as a unit, and after removal of the tub from the frame, the frame can be easily carried by a single person by getting within the frame and bodily gripping either the side or end frame members thereof with the hands.

30 In order to rigidly attach the spiders 9 and 15 to the tub, and to prevent any possibility of relative or lost motion therebetween with the consequent resulting noisy operation after continued use, the end walls 16 and 17 of the tub are pressed inwardly so as to produce depressions therein corresponding exactly in outline and in lateral dimensions to the spiders. The spiders are positioned within these depressions and snugly 35 fit therein, being permanently held in place by riveting or bolting as indicated at 18'. The depth of these depressions may be varied according to the size and weight of the tub, in the form illustrated in the drawings 40 55 the depth being such as to cause the spiders to be but partially embraced by the end walls of the tub, as clearly shown in Fig. 2. These depressions perform a dual function, not only receiving and maintaining the spiders but also serving as strengthening corrugations for the end wall of the tub.

60 The oscillating tub comprises the end walls 16, 17 and the main body portion 18 attached to said walls in any approved manner as by the seams indicated at 19. The

upper portion of the main body 18 is provided with an opening formed with a peripheral depressed lip 20 upon which the marginal flange 21 of a top or cover 22 is adapted to rest. The bottom of the main body portion 18 at its lowest portion is 70 pressed outwardly to form a trough 23, this trough gradually increasing in both width and depth from the end wall 17 to a point adjacent the end wall 16, at which point a 75 drain cock 24 communicates therewith.

Positioned above the bottom portion of the main body 18 and spaced therefrom to provide a sediment-collecting chamber 25 is a false bottom formed by the sections 26, 26', which is attached to the body 18 throughout its entire perimeter as by soldering. The false bottom is of inverted V-shape and is corrugated throughout substantially its entire extent except the space between the sections which is filled by a removable door 27 connecting the two sloping sides thereof, for providing ready access to the sediment-collecting chamber whenever desired. The door 27 extends the full width 80 of the tub being formed with depending flanges which rest upon ledges 27' and 27" provided by turning the inner edges of the section 26, 26' downwardly and laterally, the metal adjacent the edges being bent upon 85 itself, as clearly shown in Fig. 5. The central portion of the door is depressed at 27^a for the reception of the upper bar 27^b of a latch or locking device, the upper bar being rigidly secured to a lower bar provided with the oppositely extending prongs 27^c, 27^d, by a pin 27^e. The prongs 27^c, 27^d are of such length and the remaining parts of such dimensions that the prongs firmly 90 engage the lower surfaces of the ledges 27', 27", when the latch is turned to the position shown in Fig. 5 so as to securely fasten the same in position. From the above description, it is obvious that by merely turning the upper bar 27^b through an arc of 95 about ninety degrees, the prongs 27^c, 27^d will be moved out of engagement with the ledges 27', 27", after which the door may be bodily removed by lifting the same. The 100 false bottom is provided with a series of 105 perforations 28 which are disposed in the bottoms of the grooves formed by the standing ribs 29 of the corrugations.

Attached to the inner surface of the body 18 at a substantial distance above the false bottom 26, at opposite sides of the tub, are inwardly extending deflecting baffles 30, 30' for preventing the water reaching the filling opening of the top and for directing the same towards the center of the tub. The body of the tub is corrugated throughout the portions 31, 31' located between the false bottom and the baffles 30, 30', the corrugations in the body 18 forming with the corrugations of the false bottom a continuous 115 120 125 130

rubbing surface over which the clothes are constantly moved during the oscillation of the tub.

- The operation of the device is obvious from the above description of the construction thereof, functioning in a well known manner. The tub being partially filled with suds, the clothes to be washed are placed within the interior through the filling opening disposed at the top, which is then closed by the cover plate 22. Oscillation of the tub causes the clothes to be moved alternately back and forth from one side portion of the false bottom to the other side portion disposed at the opposite side of the tub. During the travel of the clothes from one side of the tub to the other a rubbing effect over the corrugations of the body of the tub and in the false bottom is secured similar to the rubbing effect produced by an ordinary washboard when washing by hand. In addition to the rubbing effect, oscillation of the tub, due to the movement of the body of water therein, causes a suction effect upon its receding end and a jet effect at its advancing end. Water and air are thus drawn downwardly through the clothes at one side of the false bottom and are forced in strong jets upwardly through the clothes at the other side of the said bottom, the water freely passing through the perforations 28, the baffle 30, 30', serving to limit the flow upwardly along the sides of the tub and to deflect the water over the clothes towards its center. Due to the fact that the false bottom 26 is rigidly secured to the body and end walls of the tub throughout its entire perimeter, no open spaces or slits are provided in which the clothes can be caught or gripped, and due to the positioning of the perforations 28 within the bottoms of the grooves of the corrugations, all deleterious action upon the clothes due to their presence is avoided. In actual operation it is found that during the oscillation of the tub, the clothes are forced to pass over the sides of the tub as well as over the false bottom 26. By providing corrugations throughout the portions 31 and 31' of the body 18, a preliminary rubbing effect is secured previous to the suction effect caused by the passage of the water downwardly through the perforations of the false bottom, and a dipping or settling effect subsequently to the forcing of the water upwardly therethrough.
- It is thus seen that the invention provides a simple, compact, and convenient combination of parts, in which the tub may be easily and readily removed from and replaced in the frame, and a tub which is extremely durable and efficient for the purpose intended, one in which there is an ample sediment-collecting chamber provided below the false bottom with means for readily carrying off any dirt and sediment removed from the clothes during the washing operation, also one free of all parts which are liable to catch or grip the clothes during movement thereof, one in which a rubbing effect is continuously obtained during the entire operation as well as the desirable suction and jet effect of the water, and a construction which is not liable to become noisy even after long continued use.
- While I have described and illustrated the preferred embodiment of the invention in accordance with the provisions of the patent statutes, it is obvious that many changes may be made in the detailed construction and exact arrangement of parts without departing from the spirit of the invention. It is therefore not intended to limit the invention beyond that specifically pointed out and defined in the appended claims.
- I claim:
1. A tub for an oscillating washing machine comprising a main body and end walls, a perforated corrugated false bottom spaced from the bottom portion of the main body and attached to said body and walls throughout substantially its entire perimeter, the main body being also corrugated throughout an appreciable extent immediately adjacent and above the false bottom.
  2. A tub for an oscillating washing machine comprising a main body and end walls, a perforated corrugated false bottom spaced from the bottom portion of the main body forming a sediment-collecting chamber and attached to said body and walls throughout substantially its entire perimeter, the main body being also corrugated throughout an appreciable extent immediately adjacent and above the false bottom, the bottom of the main body being pressed outwardly to form a trough at its central portion, the trough gradually increasing in both width and depth towards one of the end walls, and a drain cock communicating with the trough adjacent its widest and deepest portion.
  3. A tub for an oscillating washing machine comprising a main body and end walls, trunnion-supporting spiders provided with radially projecting arms attached to each of the end walls, said walls being pressed inwardly to form depressions for receiving the arms, the size and shape of the depressions corresponding to that of the arms whereby the spiders snugly fit the said depressions and are held against relative rotative movement with respect to the body of the tub.
  4. In combination in a washing machine, a supporting frame, a tub mounted for oscillation thereon, means for oscillating the tub comprising a downwardly projecting depending crank arm provided with an open-topped vertical radial slot having an abutment at its lower extremity, said crank arm being urged to assume its normal vertical depending position with its free outer end at

its lowermost point under the influence of gravity, an open-topped bearing attached to the frame in alignment with the axis of said crank arm, a cylindrical trunnion fixed to one end of the tub and journaled in the said bearing, and a trunnion block attached to the opposite end of the tub removably and

slidably fitting the radial slot of the crank arm whereby to render the tub readily removable from the frame by merely lifting ¹⁰ the same.

In testimony whereof, I sign my name.

WILLIAM L. RODGERS.
